UNITED STATES PATENT OFFICE.

FREDERICK J. BAHNI, OF PEORIA, ILLINOIS.

UTILITY TOOL.

Application filed September 24, 1923. Serial No. 664,638.

To all whom it may concern:

Be it known that FREDERICK J. BAHNI, a citizen of the United States of America, residing at Peoria, in the county of Peoria 5 and State of Illinois, has invented certain new and useful Improvements in Utility Tools, of which the following is a specification.

My invention relates to utility tools and 10 more particularly to an electrically driven hand tool adapted for drilling, engraving, milling and other work of similar character.

The object of my invention is in the provision of an electrically driven hand utility tool adapted, due to a special reduction gear means, of producing the maximum torque at the working point.

Another object of my invention is in the provision of an electrically driven hand tool adapted for use in milling and other fine work whereby the usual vibration that attends such class of tools is reduced to a minimum and the lash of the cable not transmitted to the working point.

A still further object is in the provision of a hand utility tool wherein a maximum torque is effected at the working point by means of reduction gears in the tool itself.

Yet another object of my invention is in the special construction of my utility tool wherein I have provided means for quickly releasing the chuck as well as trigger mechanism effective in such release.

Other objects of my invention will appear in the following specification taken in connection with the annexed drawings, in which:—

Figure 1 is a plan from above of my hand utility tool.

Figure 2 is a side elevation.

Figure 3 is an end elevation thereof.

Figure 4 is a sectional view taken on the line 4—4 of Figure 5.

Figure 5 is a sectional view taken on the line 5—5 of Figure 1.

Figure 6 is an enlarged detail of my special trigger mechanism effective in the release of the chuck.

Referring to the drawings:—

10 refers generally to an integrally cast member including a hand piece 11, a gear casing 12 and a housing member 13 for one of the gear members to be later described and a portion of the driving cable also to be described. The member 10 acts as a

casing for the mechanism to be hereafter described.

It may be said at this point that the present structure or tool is adapted to be used 60 in any character of work where a plurality of various shaped tools are to be used. Again, it may be said that the present tool is adapted to be held by the operator, the power means for said tool being transmitted 65 thereto by means of a flexible cable 14 in connection with any power means, not shown, usually an electric motor.

A casing for the cable is shown, or rather a portion thereof, at 15 in Figure 5, said cable casing having its reduced end portion 16 inserted within the outer end of the housing 13 and maintained in engagement therewith by means of the set screw 17 engaging the indentation 18 therein. 70 This reduced portion or cable casing provides a bearing means for the end 19 of the flexible cable. The end 20 of the flexible cable has an engagement means thereon interlocking as at 21 with the slotted portion 22 on a stub shaft 23 which rotates on the bearing 16 and has positively connected thereto the intermediate gear 26. A set screw inserted thru the housing 13 locates the bearing 17 in a positive manner therein, 75 also prevents withdrawal of the stub shaft and connected parts until removal of said screw. A second gear 27 driven by the smaller gear 26 is integrally formed as the base portion of the driving spindle 28 which 80 is slidably mounted within the hand piece 11. Means for holding the drive spindle within the gear casing and hand piece is provided in the jam collar or thrust bearing 29 which is screw-threaded as at 30 in 85 the outer end of the gear casing. A wedge screw 31 and mounting 32 therefor provides means for tightening the gear casing about the jam collar after it has been inserted therein to prevent further rotation of said 90 collar in either direction. Insertable in the opposed open end of the drive spindle is a chuck 33 and chuck holder or draw spindle 34, respectively. The chuck and holder therefor are adapted for threaded engagement as shown at 35 and as a matter of 95 fact this threaded engagement provides means for fastening the chuck in a positive position within the drive spindle. The chuck 33 has a groove 36 thereon adapted to 100 engage a lug 37 projecting from the inner side of the drive spindle. This lug and

105

110

groove connection prohibits the insertion of the chuck to its full depth within the drive spindle until the respective portions are in mesh, whereupon a threading of the drawing spindle upon the chuck draws it to its full depth within the drive spindle and fastens it in positive operative connection therewith. The chuck 33 is of formal construction and has the conventional split end 10 adapted to receive a plurality of working tools.

A trigger means for holding the cable 14 and drive spindle against rotation when it is desired to release the chuck member is shown clearly in Figures 1, 2 and 3 wherein the trigger 39 is pivoted on the set screw 40 which has a threaded engagement with a portion of the casing 12 just below the projecting end of the cable 14. This trigger 20 has an opening 41, therein, wherein the projecting end of the cable normally rotates. However, the projecting end of the stub shaft is cut away as at 42 to provide a flat portion thereon. In a similar manner one 25 of the sides 43 of the trigger is flattened to engage the flat portion 42 on the cable when the trigger is moved sidewardly as shown in dotted lines in Figure 6. To resist the sideward movement of the trigger and to 30 normally hold the flat side 42 away from the cable end, a spring 44 is fastened as at 45 to the housing 13 and also engages the trigger thru an aperture 46 therein. The trigger 39 has a thumb portion 47 thereon permitting ready movement thereof to stop the 35 rotation of the cable and consequently the drive spindle when it is desired to remove the chuck for the insertion of a new tool.

The above trigger mechanism which is 40 adapted to prevent rotation of the cable, and drive spindle has been supplied in order to permit the release of the chuck member 33 by the withdrawal of the chuck holder 34. In other words, by holding the cable from 45 rotation by means of the trigger, the drive

spindle is also held against rotation with the result that it is possible then to unscrew the chuck holder by rotating the handle portion 48 thereof, thereby releasing the chuck and hence any tool that may be held therein. 50

In view of the above description, the operation of my tool will but briefly be considered. Rotation of the cable 14 thru the reduction gears transmits movement to the driving spindle and thereby movement of 55 the chuck positioned therein by means of the chuck holder. To permit a change of tools in the chuck holder, movement of the trigger member sidewise to prevent rotation of the cable also holds the drive spindle in a set position thereby permitting unscrewing of the chuck holder and the consequent release of the chuck and tool therein.

What I claim is:—

1. In a utility tool, comprising a driving member, a tool portion connected thereto, said connection including a worm on the cable member and a gear on the tool portion, said tool portion having its operating end located at a point substantially removed 60 from the connecting means and mechanism permitting removability and engagement of plural tool members comprising a member passing through the gear member.

2. In a utility tool, comprising a driving member, a tool portion connected thereto, said connection including a worm on the driving member and a gear on the tool portion, said tool portion having its operating end located at a point substantially removed 70 from the connecting means, mechanism permitting removability and engagement of plural tool members comprising a member passing through the gear member, and a manually operable latch member adapted to 75 prevent rotation of the driving member during the tool changing operation.

In testimony whereof I affix my signature.

FREDERICK J. BAHNI.
